DESIGN FOR A PYLON SMOKER

James B. Ladd, Chicago, Ill., assignor to Cadet Smokestands Company, Des Moines, Iowa, a trust

Application January 5, 1942, Serial No. 105,030

Term of patent 14 years

To all whom it may concern:

Be it known that I, James B. Ladd, a citizen of the United States and resident of Chicago, Cook County, Illinois, have invented a new, original, and ornamental Design for a Pylon Smoker, of which the following is a specification, reference being had to the accompanying drawing, forming a part thereof.

Fig. 1 is a side elevational view of a pylon smoker showing my new design; and

Fig. 2 is a top plan view thereof; and

Fig. 3 is an end elevational view thereof.

I claim:

The ornamental design for a pylon smoker, substantially as shown.

JAMES B. LADD.
